TRAURIG, LLP

(57) **CLAIM**

The ornamental design for a shingle, as shown and described.

DESCRIPTION

FIG. 1 is a front perspective view of a shingle.

FIG. 2 is a front view of the shingle shown in FIG. 1.

FIG. 3A is a back view of the shingle shown in FIG. 1.

FIG. 3B is a magnified view of a portion of the back view of the shingle according to FIG. 1.

FIG. 4 is a right side view of the shingle shown in FIG. 1.

FIG. 5 is a left side view of the shingle shown in FIG. 1.

FIG. 6 is a top view of the shingle shown in FIG. 1.

FIG. 7 is a bottom view of the shingle shown in FIG. 1; and, FIG. 8 is a back perspective view of the shingle shown in FIG. 1.

The broken lines in the drawings illustrate unclaimed features forming no part of the claimed design.

1 Claim, 7 Drawing Sheets
